STRIP-FEEDING MECHANISM

Albert E. Maspons, Albany, N. Y., assignor to
International Cigar Machinery Company, a
corporation of New Jersey

Application May 9, 1931, Serial No. 536,277

13 Claims. (Cl. 271—2.5)

My invention relates to apparatus for feeding intermittently a continuous strip of material, from which for example, wrappers are cut for application to articles, as cigars.

5 In accordance with my invention, a reciprocating unit or carriage is provided with clamping mechanism operated in timed relation to the carriage for intermittently feeding a strip of wrapping material, specifically metal foil, cellophane or the like, by movement of the carriage in one direction.

My invention also resides in the features of construction, combination and arrangement hereinafter described and claimed.

15 For an understanding of my invention and for illustration of a preferred form thereof, reference is to be had to the accompanying drawings in which:

Fig. 1 diagrammatically and in side elevation 20 illustrates the essential elements of the feeding mechanism.

Fig. 2 is a front elevational view of apparatus shown in Fig. 1, with parts omitted for clarity.

Fig. 2a is a detail of certain parts of Fig. 2.

25 Referring to the drawings, wrapping material, as paper, tinfoil, or the like, removed from the roll 5 rests upon the stationary plate 1 and passes between the movable clamping bar 6 and co-operating plates 7 of the slide unit 2, which is 30 guided for movement parallel to the stationary plate 1 by the guide rods 3. At the beginning of the cycle of movement, the slide unit 2 is stationary in the position shown in Fig. 1 and the clamping bar 6 is out of clamping engagement 35 with the wrapping material. The tip of lever 18 is disposed in the path of movement of a pin 41 projecting from an arm 20, pivoted on shaft 21 carried by the slide unit 2 so that as the slide 2 is moved downwardly, by means hereinafter de-

40 scribed, the shaft 21, by engagement of the pin 41 of arm 20 with the tip of lever 18, is rotated in a clockwise direction, causing the forked finger 22 (Fig. 2a) which is mounted on the shaft to move the pin 23 of the sliding bar 24. The 45 resulting upward movement of the bar 24 brings the depression 24a thereof beneath the pin of a bracket 26 secured to and movable with the presser bar 6, permitting the springs 27 forcibly to depress the presser bar for clamping the 50 wrapping material against the plates 7.

Upon continued movement of the slide unit, the paper or tinfoil clamped between the plates 7 and bar 6 is pulled from the roll 5. In the meantime, after bar 6 has been released, the cam 15 55 rotates the lever 16 in a clockwise direction,

against the biasing force of the spring 40, to move the link 17 upwardly, and so effect clockwise rotation of the lever 18 which is pivoted at 19 to a stationary plate or supporting member 30, to move the tip of lever 13 out of the path of movement of the slide. At the end of the feeding stroke of the slide unit, the cam 15 moves out of engagement with the lever 16 permitting spring 40 to effect counter-clockwise rotation of lever 18 which is connected by a sliding link 31 to a lever 13 pivoted at 32 to the bearing plate or support 30. The resulting movement of lever 13 brings the tip thereof into engagement with the pin 41 at the end of arm 20, so that upon upward movement of the slide the shaft 21 rotates to 70 return the sliding bar 24 to its original position, the pin 25 cooperating with the depression in the slide bar to lift the presser bar away from clamping engagement with the paper. With the clamping bar out of engagement with the wrapping 75 material, the slide unit is returned to the position shown in Fig. 1, for another cycle of movement. Just before the carriage arrives at the position of Fig. 1, cam 15 again momentarily depresses lever 16 to move the tip of lever 18 out of the path 80 of the pin projecting from arm 20.

Preferably, while the strip of wrapping material is stationary it is cut by any suitable mechanism, generically represented by knife disc 93 to provide a wrapper for an article, such as for example, 85 a cigar. The wrapper is cut from the strip projecting below the slide unit so that at all times strip material is threaded through the slide between plates 7 and bar 6. For clarity of illustration, the wrapping strip is omitted in Fig. 2. 90 The apparatus is particularly designed for attachment to the cigar-wrapping machine disclosed in my Patent No. 1,500,143 granted July 8, 1924.

For effecting reciprocation of the slide unit, 95 there is provided a bracket fastened to the underside of slide 2 and carrying the roller 33 embraced by the outwardly curved tines or prongs of the forked end or open-ended slot of lever 11, which is connected by link 10 to lever 9 actuated by a 100 cam 8, which rotates once for each reciprocation of carriage 2. The cams 8 and 15 rotate in timed relation to each other to effect the sequence of operations previously described and may be mounted on a common shaft, which is driven at 105 a uniform rate of speed by or from any suitable motive device. The feeding or downward movement of the slide unit 2 is positively effected by the cam 8 and return movement of the slide is effected by the spring 28, the adjustable stop 34 110

determining the uppermost position of carriage 2. The cam as indicated is shaped to permit the slide unit to remain stationary for a desired interval at the ends of its stroke to permit cam 15 to bring 5 the tips of fingers 18 and 13 into the path of movement of the pin on lever 20 and to allow time for cutting of the strip.

What I claim is:

1. Strip-feeding means comprising a recipro-

cating carriage, strip-clamping structure movable therewith, a pivoted arm movable with said carriage and controlling the position of said clamping structure, and means respectively movable into and out of the path of said arm upon 15 beginning of movement of said carriage in both directions alternately to actuate said structure to clamp and release the strip.

2. Strip-feeding means comprising a recipro-

cating carriage, strip-clamping structure movable therewith, means for biasing said structure into engagement with the strip, a member movable to one position to move said structure out of clamping engagement and to another position to permit said biasing means to effect clamping 25 engagement of said structure with the strip, and means movable into and out of the path of said member for actuating the member to said first position for movement of said carriage in one direction and to said second position for reverse 30 movement of said carriage.

3. Strip-feeding means comprising a recipro-

cating carriage, strip-clamping structure movable therewith, means for biasing said structure into engagement with the strip, a pivoted member 35 movable to one position to move said structure out of clamping engagement and to another position to permit said biasing means to effect clamping engagement of said structure with the strip, and means movable in the path of movement of 40 said pivoted member and in a direction transverse to said path of movement for moving the pivoted member to said second position for feeding movement of said carriage in one direction and to said first position for return movement of 45 said carriage.

4. Strip-feeding means comprising a recipro-

cating carriage, strip-clamping structure movable therewith, a pivoted arm movable with said carriage and controlling the position of said 50 clamping structure, a pair of abutments biased to positions in the path of movement of said arm, and means operating in timed relation to said carriage for moving one of said abutments out of the path of movement of said arm after the other 55 of said abutments has been engaged by said arm to change the position of said clamping structure.

5. Strip-feeding means comprising a recipro-

cating carriage, strip-clamping structure movable therewith, a pivoted arm movable with said 60 carriage and controlling the position of said clamping structure, a pair of abutments respectively movable into and out of the path of movement of said carriage, and means operating in timed relation to said carriage to effect engagement between one of said abutments and said arm for movement of said carriage in one direction and between the other of said abutments and said arm for movement of said carriage in reverse 65 direction.

6. Strip-feeding means comprising a recipro-

cating carriage, an element movable therewith in fixed relation thereto, a lever having an open ended slot embracing said element, a rotating cam effecting pivotal movement of said lever, strip- 75 clamping structure movable with said carriage,

a member movable with said carriage and controlling the position of said clamping structure, a pair of abutments, and cam structure operating in timed relation to said cam to effect engagement between one of said abutments and said member for movement of said carriage in one direction and between the other of said abutments and said arm for movement of said carriage in reverse direction.

7. Strip-feeding means comprising a recipro-

cating carriage, strip-clamping structure movable therewith, a member mounted upon said carriage and movable to different positions to control the strip-clamping and strip-releasing movement of said structure, a pair of abutments, and means to move each of said abutments out of the path of movement of said member as said carriage approaches the limit of its travel in one direction and to move each of said abutments into the path of movement of said member as said carriage departs from its limit of travel for movement in the opposite direction.

8. Strip-feeding means comprising a recipro-

cating carriage, strip-clamping structure movable therewith, a member mounted upon said carriage and movable to different positions to control the strip-clamping and strip-releasing movement of said structure, a pair of inter-connected levers whose tips are movable in an arc intercepting the path of movement of said member, and means operating in timed relation to said carriage for actuating said levers to remove the tips of said levers from the path of said member as said carriage approaches its extreme positions and to bring the tips of said levers into the path of said member as said carriage moves from said positions.

9. Strip-feeding means comprising a carriage, strip-clamping structure movable therewith, a member mounted upon said carriage and movable to different positions to control the strip-clamping and strip-releasing movement of said structure, a cam for movement of said carriage in one direction, biasing means for effecting reverse movement of said carriage, a pair of abutments biased into the path of movement of said member, and a cam operating in timed relation to said first cam for momentarily moving said abutments out of the path of movement of said member as said carriage approaches its extreme positions.

10. Strip-feeding means comprising a recipro-

cating carriage, strip-clamping structure movable therewith adapted to engage strip-material threaded through said carriage, a member mounted upon said carriage and movable to different positions to control the strip-clamping and strip-releasing movement of said structure, a pair of abutments respectively movable into and out of the path of said member, and means for moving one of said abutments into the path of said member to actuate said structure for clamping of the strip for movement of said carriage in one direction and the other of said abutments into the path of said member for releasing the threaded strip for movement of the carriage in reverse direction.

11. Strip-feeding means comprising a recipro-

cating carriage, strip-clamping structure movable therewith, a member mounted upon said carriage and movable to different positions to control the strip-clamping and strip-releasing movements of said structure, a pair of rotatable abutments, and means to rotate each of said abutments out of the path of movement of said member as the carriage approaches the limit of its travel in one direction and to rotate each of said abutments into the path of movement of said member as said

- carriage departs from its limit of travel in the opposite direction.
12. Strip-feeding means comprising a reciprocating carriage, strip-clamping structure movable therewith, a member mounted upon said carriage and movable to different positions to control the strip-clamping and strip-releasing movements of said structure, a pair of rotatable abutments, means for biasing said abutments into the path of movement of said member, and means to rotate each of said abutments out of the path of movement of said member as the carriage approaches the limit of its travel in one direction and to rotate each of said abutments into the path of movement of said member as said carriage departs from its limit of travel in the opposite direction.
13. Strip-feeding means comprising a carriage, strip-clamping structure movable therewith, a member mounted upon said carriage and movable to different positions to control the strip-clamping and strip-releasing movements of said structure, a cam for movement of said carriage in one direction, biasing means for effecting reverse movement of said carriage, a pair of rotatable abutments, means for biasing said abutments into the path of movement of said member, and a cam operating in timed relation to said first cam for momentarily rotating said abutments out of the path of movement of said member as said carriage approaches its extreme positions.
